CLAIM

The ornamental design for a pronated box grip handle for weight training, as shown and described.

DESCRIPTION

FIG. 1 is a front elevation view showing the new, original, and ornamental design of a pronated box grip handle for weight training;

FIG. 2 is a right elevation view thereof;

FIG. 3 is a rear elevation view thereof;

FIG. 4 is a left elevation view thereof;

FIG. 5 is a bottom plan view thereof;

FIG. 6. is a top plan view thereof; and,

FIG. 7 is a perspective view thereof.

The broken lines in the form of weights and a clamp in FIG. 7 depict environmental subject matter and form no part of the claimed design. The remaining broken lines depict portions of the pronated box grip handle for weight training that form no part of the claimed design.
